CLAIM

The ornamental design for an electrical connector body, as shown and described.

DESCRIPTION

FIG. 1 is a top perspective view of an electrical connector body according to our new design;

FIG. 2 is a top plan view of an electrical connector body of our new design shown in FIG. 1;

FIG. 3 is a rear side elevational view of the electrical connector body of our new design shown in FIGS. 1-2, with the side being substantially a mirror image thereof;

FIG. 4 is a bottom plan view of the electrical connector body of our new design shown in FIGS. 1-3;

FIG. 5 is a right end elevational view of the electrical connector body of our new design shown in FIGS. 1-4; and,

FIG. 6 is a left end elevational view of the electrical connector body of our new design shown in FIGS. 1-5.
